UNITED STATES PATENT OFFICE

EDWIN P. HEWITT, OF SPOKANE, WASHINGTON; NELLIE HEWITT ADMINISTRATRIX
OF SAID EDWIN P. HEWITT, DECEASED.

VALVE STRUCTURE.

Application filed November 13, 1922. Serial No. 600,488.

To all whom it may concern:

Be it known that I, EDWIN P. HEWITT, a citizen of the United States, residing at Spokane, in the county of Spokane and 5 State of Washington, have invented new and useful Improvements in Valve Structures, of which the following is a specification.

This invention relates to improvements in pressure reducing valves more particularly designed for ammonia machines and has to do most particularly with means whereby the valve may readily be cleared from scale and other refuse acting to prevent the valve from seating.

15 It is a feature of my invention to equip such a valve structure with a valve close and seat, both relatively broad and flat, and both, in the plane of flow of the fluid when in an open position, so that the fluid will blow 20 the foreign matter off from the acting faces of said seat and closure.

By reason of these broad flat seat and closure members, such foreign matter as may 25 be interposed therebetween to prevent the closure from seating, may be so completely pulverized when said members are relatively actuated, that the pressure fluid will most effectively remove such matter when the members are in an open adjustment.

30 It is also an object of my invention to provide means accessible from the exterior of the structure for manual operation by the operator for grinding or pulverizing any scale or dross between the seat and closure 35 so that when the closure is un-seated, in the usual operation, such matter will be blown away.

A further feature of my invention consists 40 in a tubular body in which the seat is formed, and which tubular body is positively centered at both ends so that when the parts are turned into assembled relation, the seat body will not be swerved out of a truly alined position.

45 Further and additional objects and features of my invention will be more fully described in connection with the accompanying drawing and will be more particularly pointed out in and by the appended claims.

50 In the drawing:—

Fig. 1, is a vertical sectional view of a reducing valve with the device of my invention applied thereto.

Fig. 2, is a sectional view of the tubular seat body on an enlarged scale. 55

Fig. 3, is a bottom plan view of the closure.

Fig. 4, is a sectional view of a portion of the casing shown in Figure 1, with the valve structural part omitted. 60

Fig. 5, is a detail view of the valve closure.

Like characters of reference designate similar parts throughout the different figures of the drawing.

I will first describe that portion of the 65 structure which is old and well known, and which includes a casing embracing a cap section 1, and a base section 2. These sections 1 and 2, are secured together by bolts 3, and an interposed diaphragm 4, held in 70 place between said sections, is subject to the low pressure side. This diaphragm is normally actuated in one direction by means which includes a diaphragm plate 5, engaged by a spring 6. The tension of the spring 75 may be increased or decreased by a bolt 7, engaging a tension plate 8, against which one end of spring 6 abuts. Bolt 7, has threaded engagement with cap section 1, and may be locked in its adjusted position 80 by nut 9. A pusher plate 10, having a flange 11, is engaged by the diaphragm 4, and is guided by an upstanding annular flange 12, shown formed integral with base section 2. The flange 11, of pusher plate 10, has recesses 13, whereby passage of the fluid can 85 not be shut off. Pusher plate 10, is also provided with a centrally disposed closure stem engaging lug 14.

Between the top of section 2, and the 90 diaphragm 4, is formed a low pressure chamber 15, a passage 16 being in open communication therewith and being connected by a pipe 17, with low pressure side of the refrigerating line, when the device is utilized 95 in such capacity. In the base section 2, is formed a high pressure chamber 18 to which a pipe 19 is connected, and which leads from the high pressure side of the refrigerating line. The arrows indicate the flow 100 of the pressure fluid from the high toward the low pressure side.

I will next describe what constitutes the device of my invention, in combination with what has been previously described. 105

First referring to my improved valve seat,

20, designates a tubular body having a seat 21, near its normally upper end, the seat being disposed internally of said body. Ingress openings 22, are disposed below said seat 21. Now the seat end 23, is tubular and has an external diameter proportioned to closely and internally telescope an opening 24, in section 2. The opening has a recess 25 and end 23 has a shoulder 26, which 10 jointly form an annular packing cavity in which a relatively soft and yielding packing 27, is disposed. The opposite, or in the present construction, the lower end 28, seats in a recess 29, of a gland body 30. This 15 gland body is tubular and has an exteriorly threaded extension 31, which is turned into and closes the lower end of section 2. A suitable soft metal packing 32, is interposed between a polygonal portion 33, and section 20 2, which is a harder packing than 27, and is only slightly compressible.

Now it will be clear that the upper end 23, of the seat body 20, has centered abutment with section 2, and the lower end 28, is centered by the gland body, hence, when the gland body is turned home, the seat body cannot swerve from a truly centered position. The gland body also supports the seat body in position. Further, it will be 30 noted that when the gland body 30, is unturned and withdrawn from section 2, the seat body 20, can also be withdrawn. By means of this arrangement, just described, I avoid the necessity of threading end 23, into opening 24, which is a material advantage in construction and I insure the correct position of the seat body, notwithstanding this fact, by reason of said body being centered at both ends.

40 The extension 31, is hollow, and the lower end thereof forms a shoulder 34. A spindle 35 extends through a gland packing 36, tightened by plug 37, and a cap 38. Said spindle has an exteriorly disposed crank 39, which is at all times accessible to be turned by the operator, for a purpose which will be later developed. Said spindle has a flange 40, which seats on shoulder 34, and limits movement of the spindle in a downward direction. The upper end of spindle 50 35, terminates in a key 41.

I will next describe my improved closure.

My improved closure comprises a cylindrical body 42, having a plurality of oil 55 ribs 43 on the periphery thereof for engagement with the bore of seat body 20. The top 44, is the closure portion which coacts with seat 21. Now it will be seen that both the seat and closure are relatively 60 broad and flat, and in practice, I case harden both. A stem or post 45, projects axially of the closure 42, for engagement by lug 14. On the bottom of closure 42, is a groove 46, into which key 41, extends. 65 Thus, the spindle 35 is non-rotatively but

longitudinally movably connected with closure 42. I purposely fit the key loosely in groove 46 to give play, so that irrespective of the service position of the closure 42, the same may be rotated by turning the 70 crank 39. A spring 47, is interposed between the bottom of the closure 42 and the flange 40, which normally acts to engage the closure 42 against seat 21. On the periphery of body 20, abreast of admission 75 to the interior thereof, I provide a screen 48, which is usual.

Now, assuming that there is 145 pounds pressure on the high pressure side and 18 pounds on the low pressure side, it will be clear that when the low pressure drops below 18 pounds, the spring 6, will act on the diaphragm and through the post 45, to un-seat the closure 42, hence, fluid under pressure will pass in the direction indicated 80 by the arrows from the high pressure to the low pressure side. Now this flow of fluid rushing under such high pressure abreast of the flat closure and flat seat, which are in the plane of low passage, not above it nor below it, in addition to the fact that the closure face and the seat face are broad and flat, facilitates removal therefrom of scale and dross which are not stuck to these faces. Thus, it is a feature of my invention to provide broad flat seat and closure faces in the plane of flow of the fluid. However, in closing, and in other circumstances, a small piece of scale might be caught by the seating closure 42, which would prevent the latter from accurately seating. This would resultantly destroy the differential of pressure, and in valves as presently constructed, the plant would have to be shut down, the 85 valve dis-mantled, and the obstruction removed. However, with my improved device, the operator would simply impart to the crank 39, one or more turns, and rotation of the hardened closure against the hardened seat, would grind and pulverize 90 such obstruction to such a state of fineness that the closure would seat perfectly, or if not, then, on the first opening movement of the closure 42, the ground obstruction would be blown clear from the seat and closure faces. In practice, and where this device 95 has been successfully used, at least once a day, the operator imparts to the crank 39, one or more turns, irrespective of any trouble, or rather, in anticipation of any trouble, and by reason of the broad flat surfaces, the hardened faces are not only maintained clean, but uniform. This last advantage results from the fact that in turning 100 the crank 39, the operator does not stop at the same place, hence, the closure 42 is always in a new position with respect to the seat 21, rotatively speaking, and this keeps the coacting faces of the seat and closure 105 uniformly worn.

It is believed that the device of my invention will be fully understood from the foregoing, and I do not wish to be limited thereto, as regards this disclosure, except for such limitations as the claims may import.

I claim:

1. A pressure reducing valve structure comprising a casing having high and low pressure connections, a valve for controlling passage of fluid from the high to the low pressure connections and said valve comprising a relatively broad flat hardened valve seat and a correspondingly broad flat hardened closure for engagement with said seat, a tensioned diaphragm means subject to the low pressure for opening or un-seating said closure, and means accessible from the exterior of said casing for rotating said closure to grind the latter and said seat clear from scale while said valve structure is in service connection without changing the adjustment of said valve.

2. A pressure reducing valve structure comprising a casing having high and low pressure connections, a valve for controlling passage of fluid from the high to the low connection, and said valve comprising a valve seat and a closure therefor, a diaphragm means subject to the low pressure for unseating said closure, a spindle mechanism manually rotatable from the exterior of said casing and having longitudinally movable and non-rotatable connection with said closure, and a spring interposed between said closure and a part of said mechanism for normally seating said closure.

3. A combined pressure reducing and ammonia expansion valve structure comprising a casing having high and low pressure connections, a valve for controlling passage of fluid from said high to said low pressure connections and being subject to operation by the low pressure, said valve comprising a tubular seat body having a seat and having endwise abutment in said casing, a closure movable in said seat body

for coaction with said seat, a gland body secured to said casing and holding said seat body in position in said casing, and a spindle manually operable from the exterior of said casing and extending into said gland body and being operatively connected with said closure, said spindle abutting against said gland body to limit longitudinal movement of said spindle in one direction.

4. A pressure reducing valve comprising a casing having high and low pressure connections, a valve controlling passage of fluid from the high to the low connection, said valve comprising a tubular seat body having an internally disposed valve seat, a valve closure movable longitudinally in said seat body and having a groove in its lower end, a gland body fixed to said casing and engaging said seat body to maintain the latter in position and said gland body having an internal bore provided with a shoulder, a spindle rotatable in the bore of said gland body and having a flange seating on said shoulder and provided with a key engaging the groove in said closure and projecting from the exterior of said gland body, and a spring interposed between said closure and the flange of said spindle and normally acting to seat said closure.

5. A combined pressure reducing and expansion valve structure for ammonia lines, comprising in combination, a casing having high and low pressure connections, a valve for controlling passage of fluid from the high to the low connection, said valve comprising a broad flat seat member and a broad flat closure member both in the plane of flow of the fluid when said members are in separated relation, and means for actuating one of said members from the exterior of said structure when the latter is in service without changing the adjustment of said members.

In testimony that I claim the foregoing as my own, I hereby affix my signature.

EDWIN P. HEWITT.
